DESIGN FOR A LABEL CONTAINER

Maria Rosenbaum, née Boevers, Hanover,
Germany

Application July 23, 1938, Serial No. 78,677

Term of patent 14 years

To all whom it may concern:

Be it known that I, Maria Rosenbaum, née Boevers, a citizen of Germany, residing at 34 Podbielskistrasse, Hanover, Germany, have invented a new, original, and ornamental Design for a Label Container of which the following is a specification, reference being had to the accompanying drawing, forming part thereof.

The figure is a perspective view of a label container showing my new design.

The appearance of the opposite side of the article is substantially the same as that of the side shown.

I claim:

The ornamental design for a label container, as shown and described.

MARIA ROSENBAUM, NÉE BOEVERS.
